TARGET STRUCTURE FOR BARRIER GRID STORAGE TUBE

Ralph B. De Lano, Jr., and John B. Little, Poughkeepsie, and Frederick L. Stutz, Pleasant Valley, N. Y., assignors to International Business Machines Corporation, New York, N. Y., a corporation of New York

Application April 23, 1954, Serial No. 425,072

15 Claims. (Cl. 313—68)

This invention relates to electron discharge devices and in particular to improvements in memory tubes of the cathode ray type.

In an electrostatic storage tube, binary information is stored in the form of charges established on the surface of a dielectric target by potentials applied to a capacitatively coupled backing plate while the beam impinges an elemental target region. A tube of this type is disclosed in the application of A. Salecker, filed February 18, 1953, Serial No. 337,544, now U. S. Patent No. 2,795,840, granted June 18, 1957.

In establishing distinguishable charge states on the target surface, the cathode beam is directed to an elemental region and secondary electrons emitted therefrom end to be attracted to a collector electrode placed near the target end of the tube. The bombarded region tends to attain an effective potential related to that of the collector electrode and the charge thereon is determined by modulation of potential applied to the backing plate. With the backing plate held negative at the time the cathode beam is turned off, the bombarded region becomes positive with respect to the effective collector potential, whereas, if the backing plate is not modulated or modulating pulse terminated before the beam is turned off, the elemental region remains at an equilibrium potential with respect to the effective collector voltage.

In the storage tube described in the above mentioned application, a fine barrier grid electrode is placed on or near the dielectric surface to shield one elemental storage region from another and reduce the redistribution of secondary electrons. This effect occurs during bombardment of an elemental region in a tube used in the conventional Williams type system when some of the emitted secondary electrons form a space charge and tend to rain back on the target surface rather than migrate to the collector. Since some of the target regions may retain charges positive with respect to the collector, there is a tendency for these secondary electrons to redistribute themselves and neutralize the adjacent established charge states in unbombarded regions, however, this action is also considered related to the initial velocity of the secondary electrons.

To minimize this redistribution effect the barrier grid is placed in direct contact with the target surface in the structure set forth in the above mentioned application and the effective collector potential is established at a value between that applied to these two electrodes.

In determining which one of the two charge states is established in a particular region, the spot on the target is bombarded and an output signal is detected at the backing plate. It has been found that a spurious voltage also appears at the backing plate during this interval and also during the interval that the beam is turned off. This voltage increases the noise level or the degree of voltage difference obtained in determining which of the two charge states had been previously established.

Accordingly, it is an object of the present invention to provide an improved target structure for a barrier grid

2

memory tube whereby the signal to noise level ratio is increased and the ability to distinguish between representative charge states is improved.

Another object of this invention is to provide an improved means for uniformly positioning the barrier grid with respect to the dielectric target surface in reducing the effects of electron redistribution.

Still another object of this invention is to provide an improved charge storage surface for a dielectric target.

10 A further object of the invention is to provide a virtual spacing between the barrier grid electrode and the target surface in increasing the signal to noise level ratio.

Other objects will be pointed out in the following description and claims and illustrated in the accompanying drawings which disclose, by way of example, the principle of the invention and a contemplated mode of applying the principle.

In the drawings:

Figure 1 illustrates a storage tube of the barrier grid type.

Figure 2 is a view of the target structure for the tube shown in Figure 1, showing the barrier grid and target subassembly in greater detail and at right angles to the other figure.

25 Figures 3 and 4 are plan views of the barrier and collector grid subassemblies.

Referring to Figure 1, the memory tube comprises an envelope 1 of glass or other suitable material within which is positioned an electron gun 2 for forming and

30 focusing a cathode beam upon a target 3. The beam is produced by a thermionic cathode 4 and is turned on under control of an apertured control grid electrode 5. An anode electrode 6 is positioned in alignment with the beam and accelerates the electrons emitted from the

35 cathode 4. Elements 7, 8 and 9A are focus electrodes and element 9B is a shield electrode formed from apertured metal discs and spaced along the path of the beam. Pairs of vertical and horizontal deflection plates 10V and 10H respectively, direct the beam to particular elemental

40 regions on the surface of the target 3, as determined by potentials applied thereon by conventional means for producing the desired type of target scansion. A collector electrode 11 is mounted in spaced relationship to a barrier grid comprising two layers of parallel wires 12A

45 and 12B that are held in intimate contact with the bombarded surface of the dielectric target 3. A backing plate 13 is formed on the opposite target surface, for example by the evaporation of aluminum as in well known coating processes.

50 The target assembly comprises the collector and barrier electrodes, the dielectric target and the backing plate element mounted in a stainless steel frame member 14 as shown in greater detail in Figure 2. The grids 11 and 12A—12B are supported on individual frame members 15 and 16, respectively, and are so positioned within the support 14 to be separated by a distance of approximately 0.010 inch. The members 15 and 16 are fabricated of a ceramic material having a coefficient of expansion comparable to that of the grid wires in order

55 to allow equal contraction and expansion of the parts during outgassing and use. Other materials having comparable expansion characteristics may be used, however. As described in detail in the aforementioned application, the collector grid comprises strands of tungsten wire 0.0006 inch in diameter spaced at 150 turns per inch and the barrier grid comprises two layers of cross wound tungsten wires wound at 300 turns per inch. The collector wires are arranged at a 45° angle to the barrier

60 grid wires as shown in Figures 3 and 4.

65 The target 3 is formed of mica and is held in contact with the frame 15 by the first layer of barrier grid wires.

12A so that these grid wires are in direct contact with the surface facing the electron gun. It has been found that in cutting the mica target into the desired shape and dimensions, the edges have minute irregularities and the surface may not be precisely flat so that some spacing exists between the barrier grid wires and portions of the target surface. To eliminate this problem a spring member 17 is mounted within the frame member 15 so as to act against the central target area causing it to be bowed out sufficiently to hold the wires in essentially intimate contact with the target throughout their length.

The spring member 17 is positioned at right angles to the layer of wires 12A directly on the target surface, as seen in Figure 2, and thus further tends to maintain contact between individual ones of the first and second layers of wires forming the barrier grid.

As mentioned above, a noise voltage develops at the backing plate terminal and appears to be caused by the pulse applied to this electrode in the writing cycle, however, other conditions within the tube are thought to contribute to its presence. It has been found, however, that this noise voltage may be essentially eliminated by application of a coating of powdered insulating material, such as magnesium oxide, on the bombarded target surface. Other insulating oxides such as aluminum oxide may also be used rather than magnesium, and in addition, insulating materials of the class of phosphors such as magnesium tungstate and zinc sulphide have been found to provide an improved operation in this respect. With the use of phosphor materials, the backing plate may be made from a transparent conductor applied to the surface of the dielectric target so that the bombarded region may be visually observed. A further method for treatment of the target surface and one considered to produce even more satisfactory results consists of grinding or lapping the target surface with an abrasive of one of the above mentioned powdered materials, for example aluminum oxide. This roughens the surface of the mica and provides a virtual spacing between the target and the adjacent layer of grid wires equivalent to a fraction of a mill. In addition, some of the aluminum oxide particles used as the abrasive are pressed into the target surface in the lapping operation. The roughened surface or powdered insulating coating material is designated by the label 18 as shown in Figure 2.

As a result of the treatment of the target surface described and the structure for obtaining uniform contact between the treated surface and the grid wires throughout the surface, the effects of redistribution and the signal to noise level in operation of the memory tube is greatly improved.

While there have been shown and described and pointed out the fundamental novel features of the invention as applied to a preferred embodiment, it will be understood that various omissions and substitutions and changes in the form and details of the device illustrated and in its operation may be made by those skilled in the art without departing from the spirit of the invention. It is the intention, therefore, to be limited only as indicated by the scope of the following claims.

What is claimed is:

1. A cathode ray tube comprising an envelope, means within said envelope for forming an electron beam along a path, a target electrode within said envelope mounted transverse to said beam path, said target electrode including a sheet of dielectric material having a roughened surface intercepting said beam path, a first electrode comprising a layer of parallel wires in contact with said roughened surface, a second electrode positioned between said first electrode and said beam forming means, and a backing plate electrode in contact with the opposite surface of said dielectric sheet.

2. An electrostatic memory tube comprising an envelope, means within said envelope for forming and direct-

ing an electron beam along a path, a target electrode within said envelope mounted transverse to said beam path, said target electrode comprising a sheet of dielectric material having one surface coated with insulating metallic oxide particles, said surface being arranged to intercept said beam path, a backing plate electrode in contact with the opposite surface of said dielectric sheet, a barrier grid electrode comprising a layer of parallel wires positioned in contact with said coated surface, and a collector electrode positioned transverse to said beam path and spaced from said barrier grid electrode.

3. A target electrode for a cathode ray type storage tube comprising a dielectric surface, a coating of insulating metallic oxide particles on said surface, a barrier electrode including a first layer of parallel wires in contact with said coating and a further layer of parallel wires transverse to and in contact with said first layer, a collector electrode including a plurality of parallel wires arranged to bisect the angle formed between the first and second layers of wires of said barrier electrode and spaced therefrom.

4. A target electrode for a cathode ray type storage tube comprising a sheet of dielectric material having a roughened surface for intercepting an electron beam, a barrier grid electrode including a first layer of parallel wires in contact with said roughened surface and a further layer of parallel wires arranged transverse to said first layer and in contact therewith, a collector electrode including a plurality of parallel wires arranged to bisect the angle formed between wires of said barrier grid and in a plane spaced from and parallel to said further layer of wires.

5. A cathode ray tube comprising an envelope, means within said envelope for forming an electron beam along a path, a frame member, a target electrode within said envelope mounted in said frame member transverse to said beam path, said target electrode including a sheet of dielectric material having a roughened surface intercepting said beam path, a first grid electrode comprising a layer of parallel wires mounted on said frame member in contact with said roughened surface, means mounted on the back of the target electrode for bowing said sheet of dielectric material so as to maintain intimate contact between said target and said layer of wires throughout their length, a backing plate electrode in contact with the opposite surface of said target, and a second grid electrode positioned between said first grid electrode and said beam forming means.

6. A target assembly for a cathode ray type storage tube comprising a dielectric charge storage surface, a coating of insulating metallic oxide on said surface, a barrier electrode including a first layer of parallel wires in contact with said coating and a further layer of wires transverse to said first layer, means mounted on the back of the target electrode for bowing said target so as to maintain intimate contact between said coated target surface and the wires of said first layer throughout their length, and a collector electrode including a plurality of parallel wires in a plane spaced from said second layer of wires.

7. A cathode ray tube comprising an envelope, means within said envelope for forming an electron beam along a path, a frame member, a target electrode within said envelope mounted on said frame member transverse to said beam path, said target electrode including a sheet of mica having a roughened surface intercepting said beam path, a first electrode comprising a layer of parallel wires mounted in said frame member and in contact with said roughened surface, a spring member mounted on said frame and acting against the opposite surface of said target to maintain intimate contact between said wires and said roughened surface.

8. In a cathode ray type storage tube, a target electrode comprising a sheet of dielectric material, a barrier electrode comprising a plurality of parallel wires in con-

fact with one surface of said sheet, said surface being roughened to maintain a virtual spacing of less than one mil between said wires and surface.

9. In a cathode ray type storage tube, a target electrode comprising a sheet of dielectric material having a roughened surface, a barrier electrode comprising a first layer of parallel wires in contact with the roughened surface of said sheet, a virtual spacing being maintained between said first layer of wires and said surface, a second layer of wires transverse to said first layer and in contact therewith, means mounted on the back of the target electrode for maintaining contact between said second and first layer of wires and between said first layer of wires and said roughened surface, a collector electrode comprising a layer of wires spaced from said second layer and arranged to bisect the angle formed between wires of said barrier grid and spaced therefrom, and a backing plate electrode in contact with the opposite surface of said dielectric sheet.

10. A cathode ray tube comprising an envelope, means within said envelope for forming an electron beam along a path, a target electrode within said envelope mounted transverse to said beam path, said target electrode including a sheet of dielectric material having a phosphor coated surface intercepting said beam path, a first electrode comprising a layer of parallel wires in contact with said coated surface, a second electrode positioned between said first electrode and said beam forming means, and a transparent conductive backing plate electrode in contact with the opposite surface of said dielectric sheet.

11. An electrostatic memory tube comprising an envelope, means within said envelope for forming and directing an electron beam along a path, a target electrode within said envelope mounted transverse to said beam path, said target electrode comprising a sheet of dielectric material having one surface coated with a phosphor material, said surface being arranged to intercept said beam path, a backing plate electrode in contact with the opposite surface of said dielectric sheet, a barrier grid electrode comprising a layer of wires positioned in contact with said coated surface, and a collector electrode positioned transverse to said beam path and spaced from said barrier grid electrode.

12. A target assembly for a cathode ray type storage tube comprising a dielectric target having a charge storage surface, a coating of powdered insulating material on said surface, a barrier electrode including a first layer of parallel wires in contact with said coated surface and

a further layer of wires transverse to said first layer, means mounted on the back of the target electrode for bowing said target so as to maintain intimate contact between said coated target surface and the wires of said first layer throughout their length, and a collector electrode including a plurality of parallel wires in a plane spaced from said second layer of wires.

13. A cathode ray tube comprising an envelope, means within said envelope for forming an electron beam along a path, a frame member, a target electrode within said envelope mounted on said frame member transverse to said beam path, said target electrode including a sheet of mica having a phosphor coated surface intercepting said beam path, a first electrode comprising a layer of parallel wires mounted in said frame member and in contact with said coated surface, a spring member mounted on said frame and acting against the opposite surface of said target to maintain intimate contact between said wires and said coated surface.
14. In a cathode ray type storage tube, a target electrode comprising a sheet of dielectric material, a barrier electrode comprising a plurality of parallel wires in contact with one surface of said sheet, said one surface being coated with powdered insulating material to maintain a virtual spacing between said wires and surface.
15. In a cathode ray type storage tube, a target electrode comprising a sheet of dielectric material, a barrier electrode comprising a first layer of parallel wires in contact with one surface of said sheet, said sheet being coated with powdered insulating phosphor material to maintain a virtual spacing between said first layer of wires and said surface, a second layer of wires transverse to said first layer and in contact therewith, means mounted on the back of the target electrode for maintaining contact between said second and first layer of wires and between said first layer of wires and said coated surface, a collector electrode comprising a layer of wires spaced from said second layer and arranged to bisect the angle formed between wires of said barrier grid and spaced therefrom, and a transparent conductive backing plate electrode in contact with the opposite surface of said dielectric sheet.
